CEMENT SPRAY DEVICE

John E. Smith, Los Angeles, Calif.

Application March 12, 1936, Serial No. 68,361

11 Claims. (Cl. 91—44)

My invention relates primarily to a device for applying cement or like plastic materials in which the cement or the like is transported in a dry state through a hose and hydrated at the point of a nozzle and then applied in a spray form, such devices being variously called "cement guns" etc., and its prime object is the provision of means, in such devices, whereby the fluid being supplied to the stream of aggregates passing through the nozzle may be maintained at a relatively high pressure at least not lower than the line pressure, while permitting the volume to be varied.

Another object is to provide means of the above character whereby the fluid being commingled with the stream of aggregates will be caused to "fan out" or spread as it passes out of the jet into the nozzle, this "fanning out" or spreading being at right angles to the flow of the stream of aggregates, the result being a substantially perfect mixture of fluid and aggregates with a resultant uniform hydration.

Heretofore in the use of so called "cement guns" etc., in applying cement and like plastic materials, fluid has been added to the stream of aggregates, passing through the nozzle, through a plurality of openings or jets positioned radially around the nozzle and angled in the direction of flow of the aggregates and, when it was desired or found necessary to alter the proportion of fluid and aggregates, the flow of fluid was increased or decreased by means of a valve in the main supply.

This, of course, decreased or increased the pressure of the jets passing into the nozzle with the result that the fluid, in the case of decreased pressure, would fail to penetrate sufficiently into the stream of aggregates to permit a thorough commingling, the result being that the outer surface of the stream of aggregates would be too wet, and the inner portion too dry.

In the use of my invention I provide means for varying the capacity or transverse area of the jet openings as individual openings so that as the fluid supply is varied the transverse area or capacity of the individual jet openings is also varied and the pressure of the fluid passing therethrough maintained or adjusted as desired and at the same time the fluid as it passes out of the outlets is caused to "fan" or spread fanwise transversely of the stream of aggregates.

Other objects and advantages will appear hereinafter and, while I have shown and will describe the preferred form of my invention, it will be understood that I do not limit myself to

such preferred form but that various changes and adaptations may be made therein without departing from the spirit of my invention.

In the drawing accompanying and forming a part hereof:

Fig. 1 is a side elevation of a cement gun constructed according to my invention.

Fig. 2 is a left hand elevation of Fig. 1.

Fig. 3 is a central transverse section through my improved fluid control.

Fig. 4 is a central vertical section through Fig. 3 and taken at right angles thereto.

Fig. 5 is a detail of a portion of Fig. 3.

Fig. 6 is a fragmentary detail of a modified form of my invention.

Referring to the drawing my device comprises an outer housing 8 provided with an interior fluid chamber 9. Projecting from the lower portion of the housing 8, is an integral boss 10 through which is provided an opening 11, internally screw threaded for connection to a street L 12 by means of which said chamber is connected to a fluid supply pipe 13. A control valve (not shown) is inserted in the supply pipe line, the object of which will be obvious.

Provided in the opposite sides 14 and 15 of the housing 8 are openings 16 and 17, which openings are concentric relatively to each other, and mounted at its ends in these openings 16 and 17, held positioned by any suitable or desired means, such as soldering, friction or otherwise, is the jet-opening ring or carrier 19, in which are provided the radially extending jet openings 20, of which I have shown eight, equally spaced, but any other number may be used as found necessary or advisable, and any desired spacing may also be used. Provided through the carrier 19 is a passage 21 through which the aggregates are forced during admixture with the fluid. Mounted within the chamber 9 to snugly fit around the ring or carrier 19 is the jet adjusting valve member 22, through which are provided jet openings 23 adapted to coincide with the openings 20 of the ring 19 and provide a continuous passage from within the chamber 9 to the passage 21. Extending upwardly from the side of member 22 is an abutment 24, and this abutment projects through an elongated opening 25 in the wall of housing 8 and terminates at a short distance thereabove. Detachably mounted upon the housing 8 to inclose the elongated opening 25 and the abutment 24 is a closure cap 26, held positioned by screws or studs 27 and nuts 28, soldering or the like being used if found necessary or desirable to make the connection

or union therebetween watertight. Cap 26 is also provided with a removable closure plate 29. Provided in opposite ends of the cap 29 are bosses 30 and 31 and screw threadedly mounted in the 5 boss 30 is an adjusting screw 32, provided on its outer end with a hand wheel 33, a packing gland 34 being provided for insuring a fluid tight connection between the projecting end of the screw 32 and the housing or cap 26. Screw- 10 threadedly mounted in the boss 31 is an adjusting sleeve 35, provided on its outer end with a lock nut 36 by means of which said sleeve may be locked against movement relative to boss 31. Projecting through the sleeve 35, concentric 15 therewith and in screwthreaded engagement therewith is an elongated stop member 37, the inner end of which acts to limit the rotative movement of the member 22 by means of the abutment 24. The other end of the stop mem- 20 ber 37 projects beyond the outer end of the sleeve 35 and is squared or other wise adapted for the reception of or engagement by a suitable tool for rotating the same.

A lock nut 38 is provided for the member 37 25 whereby the same may be locked against relative movement with sleeve 35. Coiled around the stop member 37 between the inner end of the sleeve 35 and the adjacent side of the abutment 24 is a coil spring 39 which normally acts to 30 hold the abutment 24 against the adjusting screw 32.

While I have shown and described the jet openings 20 and 23 as being circular it will be understood that I do not intend to confine myself 35 to any specific contour but that I may also use slotted apertures extending radially or transversely or in any other manner desired or found advisable. (See Fig. 6.)

In the operation of my device should it be de- 40 sired to vary the area of the jet openings, the rotation of the adjusting screw 32 by means of the hand wheel 33 will rotate the jet adjusting valve member 22 and move its jet openings 23 into or out of register with the jet openings 20, 45 according to whether it is desired to increase or decrease the area.

Interiorly screw threaded extensions 40 and 41, projecting from the sides of housing 8 and concentric with passage 21 provide means for connection to the nozzle 42 of any suitable construction and the aggregate supply pipe or tube 43.

Having described my invention what I claim is:

1. In a device of the character described a 55 housing, having a fluid chamber therein and a connection from said fluid chamber to a fluid supply, a detachable annulus rigidly mounted in said housing and having a central opening therethrough and a plurality of radially extending 60 fluid passages connecting said central opening to said fluid chamber, an adjusting member mounted in said fluid chamber to surround said annulus and being provided with a plurality of radially extending fluid openings there adapted 65 to register with the said first fluid passages, and means for rotating said adjusting member to bring the fluid openings therein into or out of register with the fluid passages of said annulus and restrict or increase the flow of fluid there- 70 through.

2. In a cement spray device, a housing having a passage therein for dry aggregates, a fluid chamber in said housing and having a plurality of jet orifices opening into said passage, a valve 75 member movable in said chamber for simul-

taneously varying the area of all of said jet orifices, and means operable exteriorly of said housing for so moving said valve member.

3. In a cement spray device, a housing having extending therethrough a passage for dry aggregates, a fluid chamber having jet orifices arranged to direct jets of fluid under pressure into said passage, means for establishing connection of said chamber with a source of fluid under pressure, a valve member movable relative 10 to said orifices for simultaneously varying the area of said orifices, and means for moving said valve member.

4. In a cement spray device, a housing having extending therethrough a passage for dry aggregates, a fluid chamber having jet orifices opening into said passage, means providing for connection of said chamber with a source of fluid under pressure, a valve member having a plurality of openings adapted to register with and communicate 15 said jet orifices with said chamber, and means for moving said valve member to simultaneously vary the volume of the fluid jets. 20

5. In a cement spray device, a housing having a passage for dry aggregates, a fluid chamber located between the ends of and surrounding said passage and having fluid jet orifices opening into said passage, means providing for connection of said chamber with a source of supply under pressure, means at opposite ends of said 30 housing and said passage therein providing for connection of the housing with a nozzle and a dry aggregate feed conduit, a rotary valve member in said chamber and having openings which are adapted to register with said jet orifices and 35 to vary the fluid volume of the jets, and means operable exteriorly of said housing for turning said valve member.

6. In a cement spray device, a housing having a passage through which dry aggregates are 40 passed, a fluid chamber adjacent said passage and having jet orifices arranged to discharge into said passage, a movable valve member having openings adapted to be brought into and out of registration with said orifices upon movement of 45 said valve, and means operable exteriorly of said housing for moving said valve.

7. In a cement spray device, a housing having a passage therethrough for dry aggregates, a fluid chamber located between the ends of said 50 passage and including an annular wall which is removably mounted in said housing, said annular wall having a plurality of jet orifices arranged to discharge into said passage, an annular valve member surrounding and being rotatable relative 55 to said annular wall and having openings therein adapted to communicate the said orifices with the interior of said chamber, and means for rotating said valve member.

8. In a cement spray device, a housing having 60 a passage for dry aggregates, a fluid chamber in said housing, means providing for connection of said chamber with a source of fluid under pressure, and means for directing jets of fluid from said chamber into said passage including a 65 stationary member having orifices therein, a movable member having openings adapted to establish communication of said orifices with said chamber, and means operable exteriorly of said housing for moving said movable member. 70

9. In a cement spray device, a housing having a passage for dry aggregates, a fluid chamber in said housing, means providing for connection of said chamber with a source of fluid under pressure, and means for directing jets of fluid from 75

said chamber into said passage including a stationary member having orifices therein, a movable member having openings adapted to establish communication of said orifices with said chamber, and means operable exteriorly of said housing for moving said movable member, said stationary member being removable through said passage.

10. A cement spray device comprising a housing having a passage through which dry aggregates are passed, a fluid chamber adjacent said passage, adapted for connection with a source of fluid under pressure and having a jet orifice for discharging fluid into said passage, and means 15 for varying the volume of the jet while maintaining the normal fluid chamber pressure of the fluid passing therethrough comprising a valve

member movable relative to and cooperating with said orifice and means operable at will upon the exterior of said housing for adjusting said valve.

11. A cement spray device comprising a housing having a passage for dry aggregates, a fluid chamber adjacent to said passage having a jet orifice for discharging fluid into said passage, means adapted for connecting said chamber with a source of fluid under pressure and for maintaining a substantially uniform pressure therein at 10 least lower than the line pressure from said source, and means for maintaining a relatively high jet pressure while varying the volume of the jet including a valve associated with said orifice and valve adjusting means arranged for 15 actuation during cement spraying operations.

JOHN E. SMITH.
